G. H. WALKER,
SUBMARINE SIGNALING DEVICE,
APPLICATION FILED MAY 2, 1917.

Patented Apr. 8, 1919.

INVENTOR
George H. Walker,

BY
Stuart Freeman,
ATTORNEY.

UNITED STATES PATENT OFFICE.

GEORGE H. WALKER, OF WILLOW GROVE, PENNSYLVANIA.

SUBMARINE SIGNALING DEVICE.

1,300,062.

Specification of Letters Patent. Patented Apr. 8, 1919.

Application filed May 2, 1917. Serial No. 165,912.

To all whom it may concern:

Be it known that I, GEORGE H. WALKER, a citizen of the United States, residing at Willow Grove, in the county of Montgomery and State of Pennsylvania, have invented certain new and useful Improvements in Submarine Signaling Devices, of which the following is a specification.

The object of this invention is to provide 10 a device for detecting the presence of bodies submerged beneath the surface of an ocean, harbor, or river, or to indicate shallow depths when sounding during the charting of river beds, or the like.

Another object is to more particularly provide 15 a device, which can be suspended from one or more ships, and trailed through the water, and which upon encountering a submerged body lying in its path will immediately indicate the presence and location of 20 the same to those upon said ship or ships.

And another object is to provide such a device which, upon contacting with a submerged body of iron, or steel, as for instance, 25 a submarine or mine, will cling or adhere to the same, by magnetic attraction, and continue to signal the latter's presence until released therefrom.

A further object is to provide such a 30 device and mechanism connected therewith, which will give both an audible and a visible alarm or indication of the presence of the said submerged body.

And a still further object is to provide a 35 device of this character which will positively operate when coming into contact with a body when in any one of an indefinite number of positions.

These and additional objects and details 40 of the construction of the preferred embodiment of the invention are fully brought out in the following description, when read in conjunction with the accompanying drawings in which Fig. 1 is an elevational view

45 showing a series of the devices embodying the invention in its preferred form suspended beneath the surface of a body of water; Fig. 2 is a diagrammatic view showing the electrical connections for the same; Fig. 3 is 50 an enlarged detail view of one magnet unit; and Fig. 4 is an enlarged detail elevational view of the exposed end portion of one of the said magnets.

55 Referring to the drawings, a suitable frame 1 is suspended by means of spaced cables 2, or the like, from a ship (not

shown), or from a suitable support extending across the surface of a given body of water, while from said frame is suspended by means of chains 3, one or more spiders 4, 60 provided with shoulders 5, to which are secured electro-magnets 6 having soft iron cores 7.

Said magnets extend radially from said spider and are connected at their outer ends 65 by a preferably circular guard 8, which permits the magnets as a unit to roll along the side of a submerged body such as a submarine until the latter is in contact with one of the outwardly spring-pressed electric 70 switches 9 of a non-magnetic metal, such as bronze, brass, or any metal in fact other than iron and steel, said switches being pivotally mounted between spaced ears 10 carried by the magnet spool 6, and coöperating 75 with a contact point 11, also carried in a suitable manner by, yet insulated from, said spool.

The switches 9 are each provided with a centrally disposed aperture 12 through which 80 the outer end of the neighboring core 7 extends, when the said switch is pressed against the said contact point by a body with which it is in engagement. Referring to Fig. 2, a source of electric current 13 normally energizes 85 each of the electro-magnets of the respective units through wires 14 and 15, and as soon as one of these magnets thus energized comes into close proximity to a body made of iron or steel (not shown), it tends 90 to cling thereto until it is forcibly removed therefrom.

As this action takes place, the closing of the adjacent switch 9 completes a circuit through the wires 16, 17 and 18, bell 19, current source 20, and relay coils 21, thus audibly notifying those in the vicinity of the condition of affairs beneath the water's surface. By the closing of the armature 22 upon energizing the coils 21, a circuit including the source of electricity 13 and one or more lamps 23 (or other visible indicator) is closed, making both an audible and a visible warning as long as the switch 9 is in contact with the point 11. 100 105

For the purpose of maintaining the magnet units in their lowermost positions, weights 24 are secured to each of the spiders 4, while connecting said units are flexible members, such as chains 25. With this 110 arrangement, if the said units are separated a greater distance apart than the width of a

mine, submarine, or the like, which would otherwise pass between a pair of them, said connecting chains are struck by the submerged body, causing one or both of the units at the ends thereof to swing toward the said body and to come into contact therewith. If the unit strikes the body at a point between a pair of the magnet cores, the guard permits the former to roll slightly until one of the said magnet cores comes into contact with the said body, after which the former adheres to the latter, and signals this fact to the watchers above, by closing the adjacent switch 9.

15 In the understanding of the principles of this invention, it should be noted that an attempt has been made to illustrate only the essential features thereof, without endeavoring to perfect all of the details and relative sizes of the various parts, this being left to those engineers particularly qualified for such work, and it is therefore obvious that the interpretation of the several claims should not be limited to the exact form shown in the accompanying drawings.

Having thus described my invention, what I claim and desire to protect by Letters Patent of the United States is:—

1. In a submarine signaling device, an electro-magnet, and an electric switch in close proximity to said magnet, said magnet being adapted to contact with and cling to an iron or steel body, and the said switch adjacent thereto being closed thereby.

30 2. In a submarine signaling device, a plurality of radially directed normally energized electro-magnets, a yoke to secure said

magnets together, and a switch associated with each magnet adapted to be closed by body in contact with the core of the magnet adjacent thereto, and comprising a pivotably mounted contact member provided with an aperture through which the adjacent magnet core projects.

3. In a submarine signaling device, a radially directed normally energized electro-magnet, comprising a core, a relatively stationary contact member secured to said magnet, and a relatively movable pivotably mounted contact member also secured to said magnet and provided with an aperture through which said core extends.

4. In a submarine signaling device, a plurality of radially directed electro-magnets, an electric switch in close proximity to each of said magnets, said magnets being adapted to contact with and cling to an iron or steel body, and the switch adjacent thereto being closed thereby.

5. In a submarine signaling device, a plurality of radially directed normally energized electro-magnets, means to secure the same together, a circular guard substantially surrounding said magnets, a switch associated with each magnet and each switch being adapted to be closed by a body in contact with the magnet adjacent thereto.

In testimony whereof I have affixed my signature in presence of two witnesses.

GEORGE H. WALKER.
